PRESSED STEEL CROSSTIE

Filed Oct. 13, 1930

Levi Hayes
WITNESS:

Charles Leonard,
INVENTOR

BY *Victor J. Evans*
ATTORNEY

UNITED STATES PATENT OFFICE

CHARLES LEONARD, OF SOUTH CONNELLSVILLE, PENNSYLVANIA

PRESSED STEEL CROSSTIE

Application filed October 13, 1930. Serial No. 438,444.

The object of this, my present invention, is the construction of an all metal railway tie, in which the body of the tie is stamped and pressed from a single piece of steel or like metal to provide a hollow body which may be filled or partly filled with ballast, the body at the center thereof having an inwardly arched portion to prevent the lateral movement of the tie when in the roadbed, the body 16 of the tie being formed with a continuous flange on which is bolted or riveted a top plate, the top plate carrying rail plates formed with bendable tongues that are designed to be forced over the base flanges of 15 the rails for holding the rails on the ties.

To the attainment of the foregoing the invention consists in the improvement herein-after described and definitely claimed.

In the drawings:

20 Figure 1 is a top plan view of the improvement.

Figure 2 is an approximately central longitudinal sectional view therethrough.

Figure 3 is a transverse sectional view on 25 the line 3—3 of Figure 2.

The body 1 of the improved tie is of the regular length, width and height. The body is stamped and pressed from a single sheet of steel or like metal which, in the stamping and pressing operation, has its bottom centrally arched inwardly, as at 2. The ends 3 of the body 1 are arranged at a slight inclination between the sides of the said body and the upper edge of the body is formed 25 with a continuous flange 4.

Resting on the flanges 4 and riveted or bolted thereto there is the top plate 5. Before the top plate is applied the hollow body may receive therethrough a desired ballast, 40 such as sand, dirt or the like. Certain of the securing means, such as the rivets 5', pass through the corners of rail plates 6, upon which the rails 7 rest. The edges of the plates 6, inward of the corners thereof, are slotted longitudinally and the metal bounded 45 by these slits is bent to provide tongues 8 which are forced over the base flanges of the rails 7 and effectively sustain the rails on the tie.

50 The simplicity of the construction and the

advantages thereof will, it is thought, be understood and appreciated by those skilled in the art to which such invention relates so that further detailed description will not be required. Obviously I do not wish to be restricted to the precise details herein shown and described and, therefore, hold myself entitled to make such changes therefrom as fairly fall within the scope of what I claim.

Having described the invention, I claim:

A metal tie having its body portions stamped from a single piece of metal to provide a hollow rectangular member, the ends of the member being bent inwardly between the sides thereof and the open upper portion 65 of the member being formed with a continuous flange, said body having its bottom, at the center thereof, arched inwardly, a cover plate riveted to the flange, and rail engaging plates pivoted to the cover plate and to the 70 flange.

In testimony whereof I affix my signature.

CHARLES LEONARD.
